MAIL HANDLING APPARATUS

Milton A. Stovall, Silver Spring, Md., assignor to Emerson Radio & Phonograph Corporation, Jersey City, N.J., a corporation of New York

Filed Sept. 11, 1957, Ser. No. 683,284

18 Claims. (Cl. 198—30)

The present invention relates to a system and apparatus for the automatic handling of flat articles having a relatively low mass-to-area ratio, and particularly of letter mail.

In my current economy, the expeditious handling and processing of mail has become vital to the efficient conduct of business and communication. The volume of mail pieces has become so large as to encumber and literally swamp postal facilities at the larger metropolitan post offices, handling many millions of pieces of mail daily. The problems of conveying, cancelling, and sorting this great volume of varied shapes and sizes of mail pieces have heretofore not been efficiently solved, resulting in delays in delivery of mail and uneconomical utilization of space, equipment and manpower.

In solving this problem of mail handling, a first step is to provide a rapid flow of mail pieces, preferably in a stream of single units to permit subsequent individual operations on such pieces, such as cancelling, sorting, stacking and the like. In general, mail is collected at post offices or from mail boxes in batches having random orientation, and are hence first available only in bulk. A preliminary problem, with which the present invention is concerned primarily, is to convert stationary bulk mail or batches of mail into a rapidly flowing stream. A further problem is to orient the pieces of the stream in a uniform manner for subsequent operations.

The present invention will be described as particularly applied to a system for separating, transporting, and feeding letter mail, although it will be readily appreciated that the present apparatus has a wider utility than in this specific application and can be used wherever a large volume of flat light articles is to be processed.

Considering the problem in its broader aspects, the present invention is adapted to receive a helter-skelter mass of stationary or slow-moving letter mail at its input. For present purposes, such letter mail, for example, may be any relatively flat article of limited maximum dimensions, such as less than 12 inches long by 6 inches wide by $\frac{1}{4}$ inch thick, which will include all normal letters, while excluding larger flat articles, such as magazines or very large envelopes, generally termed "flats," as well as books, packages and the like. At its output, the present invention provides a rapid stream of such letter mail, transported at a high velocity providing an average flow of the order of 30,000 pieces per hour.

The present system provides apparatus by which a substantially motionless pile of random-oriented letter mail, of generally horizontal position, is converted into a stream flow of the proper average quantity or number of pieces per unit time, and with the pieces uniformly oriented, as by being in a vertical plane with the longest dimension horizontal. By way of example, such an apparatus may deliver letter mail at a rate varying between 4 and 12 pieces per second with an average of $8\frac{1}{2}$ pieces per second (500 pieces per minute), with not more than 4 letters more than half overlapped at any point in the output stream.

2

It is accordingly an object of the present invention to provide an improved system and apparatus for efficiently handling and processing a large volume of flat light articles at high speeds.

5 In particular it is an object of the present invention to provide a system and apparatus for converting a static pile or slow-moving batches of mail pieces into a stream of pieces flowing at a high average velocity to facilitate subsequent processing of the individual pieces, as by 10 automatic cancelling, sorting, facing and stacking.

These and other objects and advantages of the present invention will be more fully apparent from consideration of the following description of a preferred embodiment taken in conjunction with the appended drawings, 15 in which

Fig. 1 is a side elevation view of the input assembly of the system of the present invention;

Fig. 2 is a top plan view of the assembly of Fig. 1; 20 Fig. 3 is a fragmentary side elevation view of a portion of the assembly of Figs. 1 and 2, showing a batch metering apparatus;

Fig. 4 is a top plan view of a modification of a portion of the assembly of Figs. 1 and 2;

Fig. 5 is a side elevation view of the apparatus of 25 Fig. 4;

Fig. 6 is a fragmentary perspective view of another portion of the assembly of Figs. 1 and 2, showing another batch metering apparatus;

Fig. 7 is an enlarged fragmentary side elevation view 30 of the output end of the assembly of Figs. 1 and 2;

Figs. 1 and 2 are views of a preferred form of apparatus embodying the present invention. The input letter mail is placed either manually or by conveyor means on a slowly moving horizontal hopper belt 11 driven at constant speed by suitable motive means, not shown, coupled to a drive belt 12 rotating a drive roller 13 over which belt 11 passes. By way of illustration, hopper belt 11 may generally have a speed of $\frac{1}{2}$ inch per second. It will be understood that the input mail is merely piled on belt 11, as by dumping the contents of mail bags thereon, or by feeding from a preceding conveyor, or from culling apparatus or the like, so that the mail there is of random orientation and in many irregular layers.

At the output end of hopper belt 11, its load is dropped on an inclined weighing tray 14 from which the mail pieces slide onto an inclined conveyor belt 24. As seen in Fig. 3, tray 14 is pivotally mounted at 15 and has an arm 16 secured to it on which a counterweight 17 is adjustably mounted. Weight 17 causes the end 18 of arm 16 to rotate clockwise in the absence of a load on tray 14, so that end 18 maintains a microswitch 19 in closed position. This maintains hopper belt 11 in motion by any suitable means. For example, the motor-driving hopper belt 11 may be running continuously, 45 and coupled to belt 12 (Fig. 1) through an electrically energized clutch whose circuit is controlled by switch 19. When a sufficient batch of mail is passed to tray 14 from belt 11, it will rotate tray 14 and its arm 16 counterclockwise, to disengage arm end 18 from switch 19 to 50 stop the hopper belt 11 until the tray load has been removed. The mail holding down the tray is gradually conveyed away by conveyor belt 24, described below, so as to lighten the load on tray 14 until it is raised by weight 17 which also restarts hopper belt 11 to convey 55 more pieces to tray 14.

It is generally undesirable for long gaps to occur in supplying mail to tray 14. For this reason, suitable sensing devices, such as photocells, may be placed at the output end of hopper belt 11 to sense when no mail exists there. In response to this condition, such photocells may speed up belt 11 until mail arrives at the sensing point. Such speed-up means and their controls are 70

either conventional or are readily devised by known techniques, and need not be described in further detail here.

In this way, the first step in the flow of mail is accomplished, converting the original rough mass into batches which are singly fed to the subsequent apparatus. By way of illustration, weight 17 may be selected and set to provide for batches of the order of 25 pounds each.

In place of the hopper belt 11 and tray 14, the arrangement shown in Figs. 4 and 5 may be used where desired. In this instance, a hopper 21 having a smooth low-friction inclined surface 22 and side walls 23 is adapted to receive the bulk letter mail which slides down the inclined surface 22 toward conveyor belt 24.

In either case, belt 24 is continuously driven by a suitable motive means, similar to that of belt 11, by way of a drive belt 26. Belt 24 is preferably very wide compared to the size of the mail pieces, such as 36 to 48 inches wide, so as to get a lateral distribution of mail pieces. By way of illustration, its speed may be of the order of 14 inches per second. The belt 24 is formed of a high-friction material, or may have lateral cleats or other friction-increasing means provided, to cause the bottom letters to adhere thereto, while upper letters tend to slide back because of the relatively lower friction therebetween. To facilitate this shearing action between letters, belt 24 is made fairly steep, such as of the order of 45 degrees or more, and thereby accomplishes a rough distribution of mail pieces from hopper belt 11 or hopper 21, while simultaneously providing greater elevation for the mail pieces for later operations.

At the upper end of belt 24, and in the path of mail pieces falling over the forward edge of belt 24, is a weighing tray 28. Tray 28 is pivoted at 27 (Fig. 6) and has a counterweight bar 30 secured thereto. Weight 30 normally urges tray 28 upward. A predetermined weight of mail will pivot tray 28 downward, and it will then actuate a microswitch 25 connected in a conventional manner to stop belt 24, as by de-energizing its motor or, preferably, by de-energizing a solenoid-operated clutch as in the case of the drive for belt 11. Illustratively, tray 28 may be actuated by a batch of mail of the order of one pound in weight, and thereby serves to convert the larger batches from tray 14 to smaller batches. If belt 24 is stopped, it will no longer take the load from prior weighing tray 14, which will then load up to its operating weight before stopping hopper belt 11.

These smaller batches from tray 28 are dropped onto a further horizontal conveyor belt 29 (Fig. 7) continuously driven in any suitable manner, as by a motor through a suitable transmission means. The belt 29 and its associated apparatus serve to convert the small batches of mail into still smaller batches, approximating an irregular stream, which is then formed into stream flow. The speed of belt 29 may illustratively be of the order of 5 inches per second, which is smaller than that of belt 24 to encourage an ample supply of pieces for subsequent operation, despite irregularities in the volume or feeding of mail supplied to the input of belt 24.

Mounted over the forward end of belt 29 is a drum 34 continuously rotated by suitable means, as by a further drive belt 33 from a suitable motor. Drum 34 has a plurality of flexible fingers 36 secured thereto, which successively wipe letters from belt 29 into a curved chute 37. Fingers 36 are formed of high-friction material, and tend to engage and move forward only the uppermost letter if several are piled up thereunder, since the coefficient of friction between a finger and a letter is much higher than that between two letters. The tips of the fingers 36 may be made especially flexible, and the remainder resilient, so that the tips will contact a larger area of letter for greater friction, while the resilient remainders tend to exert greater pressure on the letters, also for better friction between tip and letter. Prefer-

ably only a few fingers 36 are placed in a lateral line across belt 29 (three and four being illustrated) to have at most only about that number of letters simultaneously ejected into chute 37. By way of example, drum 34 may rotate at a speed of the order of 35 revolutions per minute, to move fingers 36 much faster than belt 29 travels. This speed also determines the average rate of flow of mail pieces. Thus, the 14 fingers illustratively shown, rotating at 35 revolutions per minute, provide approximately 500 operations per minute or 30,000 per hour, corresponding to that many letters per hour if drum 34 is continuously supplied and sends out a letter for each finger operation.

Suitable means are provided to stop conveyor belt 29 while fingers 36 engage letters thereon, thereby increasing the degree of separation of letters. One form of such means is shown most clearly in Fig. 7, and constitutes a plurality of wire feelers 31 located approximately over the area contacted by fingers 36, but between the various fingers. These feelers 31 form a type of thickness gauge, and sense when too thick a pile of letters is beneath the fingers 36, in which case one or more of the feelers 31 will actuate its microswitch 32. The microswitches are, by way of example, in series with the control for the drive of belt 29, and upon actuation of any switch 32, belt 29 is stopped, to halt the flow of batches of mail to the fingers 36 until those fingers have cleared the mail directly beneath them. In this way, jamming of letters beneath fingers 36 is avoided, and the batches of letters arriving at drum 34 are separated into individual letters. It will be understood that other suitable desired means for stopping belt 29 may be used, such as photo-electric sensors, etc.

Up to this point, the mail pieces have been handled flat, with their large surfaces resting on the belts 11, 24 and 29, and with no attempt at orientation, in order to obtain a rough conversion from a random mass or pile on hopper belt 11 or in hopper 21 to a crude stream; still uneven in flow, and with possible overlappings. Chute 37, however, by suitable forming, turns the pieces by 90 degrees to a vertical plane, between guides 38, below which is a horizontal conveyor belt 39 continuously rotated on rollers or drums such as 41 by suitable motive means. The mail pieces ejected by fingers 36 thereby fall on edge onto belt 39 and are conveyed by it on edge; generally an orientation function is accomplished here, since pieces falling on their long sides are stable, and continue in that condition, whereas pieces falling on their short edges are generally unstable, and the inertia effect produced by belt 39 abruptly engaging a lower short edge causes a turning movement about the center of gravity of the piece, which tumbles it to its more stable position with longer edge horizontal. As an added orienting means, a "knockdown" can be placed over guides 38, spaced above belt 39 by somewhat less than the maximum mail piece width (illustratively 6 inches) so as to knock over any letters projecting above this amount. Alternatively, stumbling rolls may be used for causing up-ended letters to turn to their long sides, or beaded chains, or the like, which will yield to the mail pieces to minimize possible jams, may be suspended in between guides 38, suitably spaced from belt 39, to accomplish the same purpose. Illustratively, belt 39 may have a speed of the order of 35 inches per second, which stretches out and tends to separate the mail pieces considerably.

The apparatus described has thus converted a random pile of mail pieces, generally lying flat or horizontal, into a stream flowing horizontally with the mail pieces maintained vertically, and oriented with their long axes horizontal. This stream has a high and generally uniform average rate of flow, illustratively of the order of 30,000 pieces per hour, and may be readily supplied to subsequent apparatus for utilization and further processing.

While specific forms of weighing device have been illus-

trated above, it will be understood that other known form of such device may be used as desired.

Since many variations of the foregoing described apparatus can be readily devised without departing from the spirit of the present invention, it is to be understood that this description is illustrative only, and is not to be construed in a limiting sense, the present invention being defined solely by the appended claims.

What is claimed is:

1. Mail-handling apparatus for converting bulk letter mail into a high average flow of substantially separated and oriented mail pieces comprising a hopper conveyor belt operating at a first low speed and adapted to receive said bulk mail in random fashion, means including a weighing device at the end of said hopper belt adapted to receive mail from said belt and responsive to a predetermined first weight of mail for stopping said hopper belt upon occurrence of said first weight upon said weighing device, an inclined separating conveyor belt, said weighing device being adapted to discharge said first weight of mail upon said separating belt, whereby said bulk mail is separated into batches corresponding to said weight, said separating belt having high surface friction whereby said mail pieces tend to separate out by the slippage of upper pieces relative to pieces therebeneath, said separating belt operating at a substantially higher speed than that of said hopper belt, means comprising a further weighing device in the path of mail pieces discharging from said separating belt for stopping said separating belt in response to the discharge of a second substantially smaller predetermined weight of mail from said separating conveyor upon said second weighing device, a further horizontal conveyor belt, said second weighing device being adapted to discharge said second weight of mail upon said further belt, whereby each of said batches is converted into a plurality of smaller batches corresponding to said second weight, said further belt having a lower speed than that of said inclined separating belt, a plurality of high-friction flexible fingers mounted pivotally about an axis parallel to and across said further belt, means for continuously rotating said fingers at a high rate of speed to brush the surface of said further belt and to brush off single mail pieces therefrom, a curved chute in the path of said brushed-off mail pieces for rotating said mail pieces into a vertical plane, a horizontal output conveyor beneath said chute for transporting said pieces on edge, and means responsive to the occurrence of a predetermined thickness of mail pieces in the zone of operation of said fingers for stopping said further conveyor belt until all mail pieces are removed from said zone.

2. Mail-handling apparatus for converting bulk letter mail into a high average flow of substantially separated and oriented mail pieces, comprising means for converting said bulk mail into batches of a first predetermined weight and for conveying said batches at a first speed, an inclined separating conveyor belt, said first means being adapted to discharge said batches upon said separating belt, said separating belt having high surface friction whereby said mail pieces tend to separate out by the slippage of upper pieces relative to pieces therebeneath, means comprising a weighing device in the path of mail pieces discharging from said separating belt for stopping said separating belt in response to the discharge of a second substantially smaller predetermined weight of mail from said separating conveyor upon said weighing device, a further horizontal conveyor belt, said weighing device being adapted to discharge said second weight of mail upon said further belt, whereby each of said batches is converted into a plurality of smaller batches corresponding to said second weight, said further belt having a lower speed than that of said inclined separating belt, a plurality of high-friction flexible fingers mounted pivotally about an axis parallel to and across said further belt, means for continuously rotating said fingers at a high

rate of speed to brush the surface of said further belt and to brush off single mail pieces therefrom, a curved chute in the path of said brushed-off mail pieces for rotating said mail pieces into a vertical plane, a horizontal output conveyor beneath said chute for transporting said pieces on edge, and means responsive to the occurrence of a predetermined thickness of mail pieces in the zone of operation of said fingers for stopping said further conveyor belt until all mail pieces are removed from said zone.

3. Mail-handling apparatus for converting bulk letter mail into a high average flow of substantially separated and oriented mail pieces comprising an inclined separating conveyor belt adapted to have said bulk mail supplied thereto, said separating belt having high surface friction whereby said mail pieces tend to separate out by the slippage of upper pieces relative to pieces therebeneath, means comprising a weighing device in the path of mail pieces discharging from said separating belt for stopping said separating belt in response to the discharge of a predetermined weight of mail from said separating conveyor upon said weighing device, a further horizontal conveyor belt, said weighing device being adapted to discharge said weight of mail upon said further belt, whereby said bulk mail is converted into a plurality of batches corresponding to said weight, said further belt having a lower speed than that of said inclined separating belt, a plurality of high-friction flexible fingers mounted pivotally about an axis parallel to and across said further belt, means for continuously rotating said fingers at a high rate of speed to brush the surface of said further belt and to brush off single mail pieces therefrom, means in the path of said brushed-off mail pieces for rotating said mail pieces into a vertical plane, a horizontal output conveyor beneath said last means for transporting said pieces on edge, and means responsive to the occurrence of a predetermined thickness of mail pieces in the zone of operation of said fingers for stopping said further conveyor belt until all mail pieces are removed from said zone.

4. Apparatus as in claim 3 wherein said bulk-mail-supplying means comprises a hopper chute.

5. Mail-handling apparatus for converting bulk letter mail into a high average flow of substantially separated mail pieces, comprising an inclined separating conveyor belt adapted to have said mail supplied thereto, said separating belt having high surface friction whereby said mail pieces tend to separate out by the slippage of upper pieces relative to pieces therebeneath, said separating belt operating at a substantially higher speed than that of said hopper belt, means comprising a weighing device in the path of mail pieces discharging from said separating belt for stopping said separating belt in response to the discharge of a predetermined weight of mail from said separating conveyor upon said weighing device, a further horizontal conveyor belt, said weighing device being adapted to discharge said weight of mail upon said further belt, whereby said mail is converted into a plurality of batches corresponding to said weight, said further belt having a lower speed than that of said inclined separating belt, a plurality of high-friction flexible fingers mounted pivotally about an axis parallel to and across said further belt, means for continuously rotating said fingers at a high rate of speed to brush the surface of said further belt and to brush off single mail pieces therefrom, and means responsive to the occurrence of a predetermined thickness of mail pieces in the zone of operation of said fingers for stopping said further conveyor belt until said mail pieces are removed from said zone.

6. Mail-handling apparatus for converting bulk letter mail into a high average flow of substantially separated and oriented mail pieces, comprising means for converting said bulk mail into batches of a first predetermined weight and for conveying said batches at a first speed, means for modifying each of said first batches to

form therefrom a plurality of smaller batches, a horizontal conveyor belt for conveying said smaller batches at higher speed, a plurality of high-friction flexible fingers mounted pivotally about an axis parallel to and across said belt, means for continuously rotating said fingers at a high rate of speed to brush the surface of said belt to brush off single mail pieces therefrom, a curved chute in the path of said brushed-off mail pieces for rotating said mail pieces into a vertical plane, a horizontal output conveyor beneath said chute for transporting said pieces on edge, and means responsive to the occurrence of a predetermined thickness of mail pieces in the zone of operation of said fingers for stopping said further conveyor belt.

7. Mail-handling apparatus for converting bulk letter mail into a high average flow of substantially separated mail pieces, comprising means for converting said bulk mail into batches of a first predetermined weight and for conveying said batches at a first speed, means for modifying each of said first batches to form therefrom a plurality of smaller batches, a horizontal conveyor belt for conveying said smaller batches at higher speed, a plurality of high-friction flexible fingers mounted pivotally about an axis parallel to and across said further belt, means for continuously rotating said fingers at a high rate of speed to brush the surface of said further belt and to brush off single mail pieces therefrom, and means responsive to the occurrence of a predetermined thickness of mail pieces in the zone of operation of said fingers for stopping said further conveyor belt.

8. Mail-handling apparatus for converting bulk letter mail into a high average flow of substantially separated and oriented mail pieces, comprising an inclined separating conveyor belt, means for supplying said bulk mail to said separating belt, said separating belt comprising means for distributing said bulk mail lengthwise thereof, a further horizontal conveyor belt, means for supplying said mail to said further belt, a plurality of high-friction flexible fingers mounted pivotally about an axis parallel to and across said further belt, means for continuously rotating said fingers at a high rate of speed to brush the surface of said further belt to brush off single mail pieces therefrom, a curved chute in the path of said brushed-off mail pieces for rotating said mail pieces into a vertical plane, a horizontal output conveyor beneath said chute for transporting said pieces on edge, and means responsive to the occurrence of a predetermined thickness of mail pieces in the zone of operation of said fingers for stopping said further conveyor belt.

9. Mail-handling apparatus for converting bulk letter mail into a high average flow of substantially separated mail pieces, comprising an inclined separating conveyor belt, means for supplying said bulk mail to said separating belt, said separating belt comprising means for distributing said bulk mail lengthwise thereof, a further horizontal conveyor belt, means for supplying said distributed mail thereto, a plurality of high-friction fingers mounted pivotally about an axis parallel to and across said further belt, means for continuously rotating said fingers at a high rate of speed to brush the surface of said further belt to brush off single mail pieces therefrom, and means responsive to the occurrence of a predetermined thickness of mail pieces in the zone of operation of said fingers for stopping said further conveyor belt.

10. Mail-handling apparatus for converting bulk letter mail into a high average flow of substantially separated and oriented mail pieces, comprising a conveyor belt, means for conveying said bulk mail in separated batches to said conveyor belt, a plurality of high-friction flexible fingers mounted pivotally about an axis parallel to and across said belt, means for continuously rotating said fingers at a high rate of speed to brush the surface of said belt to brush off single mail pieces therefrom, means in the path of said brushed-off mail pieces for rotating said

mail pieces into a vertical plane, a horizontal output conveyor beneath said last means for transporting said pieces on edge, and means responsive to the occurrence of a predetermined thickness of mail pieces in the zone of operation of said fingers for stopping said further conveyor belt.

11. Mail-handling apparatus for converting bulk letter mail into a high average flow of substantially separated mail pieces, comprising a conveyor belt, means for conveying said bulk mail to said conveyor belt, a plurality of high-friction flexible fingers mounted pivotally about an axis parallel to and across said belt with said fingers adapted to brush the surface of said belt, means for continuously rotating said fingers at a high rate of speed to brush the surface of said belt in the direction of movement of said belt to brush off single mail pieces therefrom, and means responsive to the occurrence of an excessively thick batch of mail pieces in the zone of operation of said fingers for stopping said conveyor belt.
12. Mail-handling apparatus for producing a high average flow of substantially separated and oriented mail pieces comprising a conveyor belt adapted to have mail pieces supplied to it in irregular fashion, a plurality of high-friction fingers mounted pivotally about an axis parallel to and across said belt and adapted to brush the surface of said belt, means for continuously rotating said fingers at a high rate of speed to brush the surface of said belt in the direction of its movement to brush off single mail pieces therefrom, a curved chute in the path of said brushed-off mail pieces for rotating said mail pieces into a vertical plane, a horizontal output conveyor beneath said chute for transporting said pieces on edge, and means responsive to the occurrence of an excessively thick batch of mail pieces in the zone of operation of said fingers for stopping said first-mentioned conveyor belt.

13. Mail-handling apparatus for producing a high average flow of substantially separated mail pieces, comprising a conveyor belt adapted to have mail pieces supplied to it in irregular fashion, a plurality of high-friction flexible fingers mounted pivotally about an axis parallel to and across said belt and adapted to brush the surface of said belt, means for continuously rotating said fingers at a high rate of speed to brush the surface of said belt in the direction of its movement to brush off single mail pieces therefrom, and means responsive to the occurrence of an excessively thick batch of mail pieces in the zone of operation of said fingers for stopping said conveyor belt.

14. Mail-handling apparatus for producing a high average flow of substantially separated and oriented mail pieces comprising a conveyor belt adapted to have mail pieces supplied to it in irregular fashion, a plurality of high-friction flexible fingers mounted pivotally about an axis parallel to and across said belt and adapted to brush the surface of said belt in its direction of movement to brush off single mail pieces therefrom, a curved chute in the path of said brushed-off mail pieces for rotating said mail pieces into a vertical plane, and a horizontal output conveyor beneath said chute for transporting said pieces on edge.

15. Mail-handling apparatus for producing a flow of substantially separated mail pieces comprising a conveyor belt adapted to have mail pieces supplied to it in irregular fashion, a plurality of high-friction flexible fingers mounted pivotally about an axis parallel to and across said belt and adapted to brush the surface of said belt, and means for continuously rotating said fingers at a high rate of speed to brush the surface of said belt in the direction of movement of said belt to brush off single mail pieces therefrom.

16. Mail-handling apparatus for converting bulk letter mail into a high average flow of substantially separated and oriented mail pieces, comprising means for converting said bulk mail into batches of a first predetermined

weight and for conveying said batches at a first speed, means for modifying each of said first batches to form therefrom a plurality of smaller batches, a horizontal conveyor belt for conveying said smaller batches at higher speed, means operating at a predetermined zone of said belt for discharging single mail pieces from said belt, means responsive to occurrence of an excessively thick batch of mail pieces at said zone for stopping said belt, and means for orienting said single mail pieces in a vertical plane.

17. Mail-handling apparatus for converting bulk letter mail into a high average flow of substantially separated mail pieces, comprising means for converting said bulk mail into batches of a first predetermined weight and for conveying said batches at a first speed, means for modifying each of said first batches to form therefrom a plurality of smaller batches, a horizontal conveyor belt for conveying said smaller batches at higher speed, means operating at a predetermined zone of said belt for discharging single mail pieces from said belt, and means responsive to occurrence of an oversupply of mail pieces at said zone for stopping said belt.

18. Apparatus for converting a mass of flat light articles into a high average flow of substantially separated articles, comprising an inclined separating con-

5

10

veyor belt, means for supplying said mass of articles to said separating belt, said separating belt comprising means for distributing said mass of flat articles lengthwise thereof, a further horizontal conveyor belt, means for supplying said distributed articles thereto, a plurality of high-friction fingers mounted pivotally about an axis parallel to and across said further belt, and means for continuously rotating said fingers at a high rate of speed to brush the surface of said further belt to brush off single articles therefrom.
